UNITED STATES PATENT OFFICE.

CONRAD A. GROTE, OF ST. LOUIS, MISSOURI.

BULLET.

1,114,878.

Specification of Letters Patent. Patented Oct. 27, 1914.

Application filed February 24, 1914. Serial No. 820,443.

To all whom it may concern:

Be it known that I, CONRAD A. GROTE, a citizen of the United States, and resident of St. Louis, Missouri, have invented certain new and useful Improvements in Bullets, of which the following is a specification.

This invention relates to improvements in a bullet for shot-gun shells, and has for its object a bullet or slug constructed of a metal such as lead and the like. The body portion having a plurality of projecting ridges formed on the greater portion of its length, the fore part of the bullet being tapered and the said bullet is provided with a central hole or bore which hole is preferably arranged at a slight taper, the back being slightly larger in diameter than the front end.

A further object of my invention is to construct a bullet which is to be placed in that portion of a shot-gun shell which has ordinarily been used for the location of shot. The said bullet being in position between the wads supporting the powder and the thin wad located in the shell in front of the bullet and held in position by crimping the edge of the shell.

A further object of my invention is to provide a bullet having a central bore and projecting ridges or wings located on its outer periphery; the fore part of the bullet being tapered and said bullet is designed to be used in connection with shot-gun shells, which bullet may be readily inserted in the shell in the place ordinarily occupied by the shot. The said bullet is sharpened and proportioned to protect the interior of the gun-barrel in which the shell is exploded. The bullet is designed to freely fit into the breech of a shot-gun and the wings or projections are so arranged and of such material as to be slightly compressed and give when the bullet is passing through the choke of the barrel. And by this arrangement the bullet passes through the barrel on a direct straight line and is prevented from turning or twisting, and the tapered front end or nose of the bullet will strike the object and the movement of said bullet through the air is directed on a straight line instead of twisting.

Figure 1, is a vertical sectional view of my invention showing an ordinary shot-gun shell with my improved bullet in position. Fig. 2, is a detail side view of the bullet.

Fig. 3, is a front end view of the same. Fig. 4, is a perspective view of the bullet.

Referring to the drawings in detail, 5 indicates an ordinary shot-gun shell, 6 the powder, 7 the wads which support the powder in position, 8 my improved bullet, 9 a wad located in front of the bullet, and 10 the turned or crimped end of the shell.

The bullet which is the essential feature of my invention consists of a body portion 11, constructed of a material such as lead or the like. The fore part being tapered as indicated by the numeral 12, forming a point or nose, the said point terminating on a vertical line 13, which is approximately the width of the central bore 14. The bore 14, extends centrally through the body 11, the front end being smaller in diameter than the rear end 15. The object of this slightly tapered opening is that when the bullet strikes the object a core naturally is formed in the bore and by means of having its rear end slightly larger permits the core to pass through the same uncongested and thereby prevents packing and also prevents retard- 80 ing of the passage of the bullet.

The outer surface of the body 11 of the bullet is provided with a plurality of projecting ridges 16, which are preferably four in number and arranged integral with the body, the forward end of the ridges are pointed and tapered as indicated by the numeral 17, forming a sharp cutting edge 18, which assists in permitting the bullet to enter the object with much less resistance than if the front surface was blunt. These ridges or wings assist the bullet in passing through the air after discharge from the gun-barrel on a perfect direct line preventing a twisting movement and the opening in the bullet while passing through the air causes the air which passes through the central opening to act as a guide line.

By practical experiment and demonstration I have found the bullet to enter the object nose first, and the bullet when extracted was provided with a core of the material through which it penetrated, and the hole through the object distinctly disclosed four grooves showing the passage of the four ridges or wings.

It has been found in some instances that the tapered nose portion of the bullet may be provided with a thin steel shell which is to be used in instances where a bullet of 110

this character might be adapted as a projectile for cannon.

Having fully described my invention what I claim is:

5. 1. A bullet for shot-gun shells comprising a hollow body portion, a central tapered bore, the forward portion of said body portion being tapered, a plurality of ridges formed integral with the body portion extending longitudinally therewith, the front ends of said ridges being sharpened and on an angle approximately on a line with the tapered end of the body portion, substantially as specified.
10. 2. A bullet for shot guns comprising an

elongated body portion, a front blunt tapered nose, a central tapered bore formed in the body its largest diameter being at the base; four integral ribs formed on the periphery of the body portion, the front ends 20 being sharpened and terminating on a line with the tapered nose, substantially as specified.

In testimony whereof, I, have signed my name to this specification, in presence of 25 two subscribing witnesses.

CONRAD A. GROTE.
